UNITED STATES PATENT OFFICE.

AUGIE L. HANSEN, OF EVANSTON, ILLINOIS, ASSIGNEE TO CHICAGO TITLE & TRUST CO., TRUSTEE, A CORPORATION OF ILLINOIS.

MASSAGE DEVICE.

1,211,576.

Specification of Letters Patent. Patented Jan. 9, 1917.

Application filed January 5, 1912. Serial No. 669,566.

To all whom it may concern:

Be it known that I, AUGIE L. HANSEN, citizen of the United States, residing at Evanston, in the county of Cook and State of Illinois, have invented certain new and useful Improvements in Massage Devices; and I do hereby declare the following to be a full, clear, and exact description of the invention, such as will enable others skilled in the art to which it appertains to make and use the same.

This invention has for its object to provide an improved manually operated vacuum massage device, and consists in the features of construction and combinations of parts hereinafter fully described and particularly claimed.

In the accompanying drawings illustrating a suitable embodiment of the invention: Figure —1— is a side elevation of a device constructed in accordance with the invention. Fig. —2— is a central longitudinal section of the same on the line 2—2 of Fig. —1—.

My invention has for its main object to provide a massage device which is easily operated to produce a relatively high degree of vacuum and in which the pressure exerted by the hands in operating the device serves to press the nozzle against the portion of the body to which it is applied.

The device comprises the cylinder A which terminates at its upper end in a tapered end portion B having a central opening through which the rod C of the piston D passes which is reciprocably movable in said cylinder. Within said tapered portion B is a plate or head E having a tapered flange F, said head E serving as a seat for one end of the helical spring G which bears upon the piston at its other end to maintain the latter normally at the lower limit of its movement. The piston D may be constructed in any convenient manner and is provided with a cup washer H by means of which a fluid-tight joint between the piston and the inner circumferential wall of the cylinder is maintained. Mounted upon said cylinder or casting externally of the same is a ring I carrying two diametrically opposite projections J to which two hand levers K are pivotally secured by means of screws L passing through openings in the free ends of the arms M of said levers K. Each of said levers K is connected with the piston rod C,

adjacent the upper end thereof, by means of a pair of toggle levers N which are pivotally secured at one end to said piston rod C and at their other ends to said respective hand levers K in any suitable manner, the pivotal connections thereof with said levers K being disposed at a lower elevation or nearer adjacent the cylinder than the pivotal connections thereof with said rod C, when the latter is disposed at the lower limit of its movement, whereby, when said hand levers are moved toward each other, relative reciprocal movement will be imparted to the cylinder and piston against the action of said spring. The said cylinder A is open at one end and said open end portion is adapted to receive sleeves O, preferably made of rubber, and which may be provided with nozzles of various shapes and sizes depending upon the purpose for which the same are adapted to be used and the parts of the body or place thereon to which the same may be intended to be applied. Said sleeves O are slipped over the open end portion of said cylinder A and are held in place thereon by friction and by the vacuum produced within the cylinder when the mouth portions of said nozzles are applied to the skin and the piston is moved by moving the hand levers K toward each other. The said hand levers K are preferably provided with roughened or knurled outer faces to prevent a slipping of the hands thereon while operating the device, and are preferably also equipped with tangibly appreciable means such as the curved arms P adapted to engage one or more fingers of the hand to maintain the latter in a desirable position for exerting a maximum leverage when operating the device.

The operator may obviously move the piston to any desired extent to produce a vacuum within the cylinder of such degree as may be desired. The relative positions of the several parts of the device are such as will cause the nozzles to bear more firmly on the skin as the levers K are moved toward each other without causing the cylinder to turn on its longitudinal axis during such movement, this being essential to the production of the best results.

The device is very simple, efficient and easily operated.

I claim as my invention:

A massaging device comprising a cylinder,

a piston slideable therein, a spring resisting the movement of the piston in one direction, manually operable means for moving the piston against the resistance of said spring, 5 a flexible tubular extension for the mouth of the cylinder, and guard means associated with said manually operable means for preventing a slipping of the hand operating the latter, said guard means enabling the user 10 simultaneously to operate the piston and to force the said extension firmly against the skin surface which is being massaged, said manually operable means including a

piston rod and levers pivoted upon the cylinder at opposite sides of said rod substantially symmetrically of the latter, whereby the axis of the piston passes substantially across the palm of the hand operating the device. 15

In testimony whereof I have signed my name in presence of two subscribing witnesses.

AUGIE L. HANSEN.
